UNITED STATES PATENT OFFICE

2,427,279

TRANSPORTATION LOAD AND METHOD OF
PREPARING THE SAMEDon F. Hedges, Crown Point, Ind., assignor to
Carnegie-Illinois Steel Corporation, a corpora-
tion of New Jersey

Application October 2, 1944, Serial No. 556,842

6 Claims. (Cl. 105—367)

1

This invention relates to a transportation load and method of preparing the same and is especially adapted for heavy strips, deformed bars and like material, which are longer than a railway car. In shipping this long material it is necessary to resort to what is known as double or triple car loading in which an empty car is inserted in the train, the long material from a loaded car projecting over the empty car. In preparing such loads it is necessary to so load the car that the load will be solidly held together, will not shift in transit, and will be in units of a size that can be handled by both the shipper and the receiver. It should be easy to put the blocking and the stripping in place and remove it without damaging the car or material. Formerly the load was fastened to the floor by long bolts which passed through holes in the floor and to which nuts were screwed beneath the car. To insure that these bottom nuts did not come off it was necessary to burr the threads on the lower ends of the bolts and this made it difficult to unload the car.

It is an object of this invention to prepare the load so that the car will not be damaged.

Another object is to prepare the load so that the minimum of time, labor and material is required.

A still further object is to use a bundle of objects which is shorter than the car length to act as an anchor for holding down the oversized bundle.

These and other objects will be more apparent after referring to the following specification and attached drawings, in which:

Figure 1 is a top plan view of the load;

Figure 2 is a sectional view taken on the line II—II of Figure 1;

Figure 3 is a sectional view taken on the line III—III of Figure 2;

Figure 4 is a sectional view taken on the line IV—IV of Figure 2; and

Figure 5 is a sectional view taken on the line V—V of Figure 2.

Referring more particularly to the drawings, the reference numeral 2 indicates a loaded railway car which is positioned against a car 4 over which the load extends. In loading the car, cross timbers 6 are nailed to the floor 8 of the car 2 and a bundle 10 of objects shorter than the car, securely strapped together as a unit with straps 12, is then positioned lengthwise along the center of the car on the cross timbers 6. A long cross timber 14 is then positioned across the walls of the car at the end adjacent the car 4 and a sepa-

2

rator timber 16 is positioned on top of bundle 10 at the opposite end of the car. A bundle 18 of objects longer than the car securely strapped together as a unit with straps 20 is then positioned 5 in the car 2 on top of the long cross timber 14 and separator 16 with its end extending out over empty car 4. A built-up separator 22 is then inserted between bundles 10 and 18 above the center timber 6. As best shown in Figures 2 and 5, this separator 22 consists of a top piece 24 which 10 is fastened to a bottom piece 26 by means of uprights 28. The diagonal pieces 30 strengthen the assembly. The bundle 18 is then strapped securely to cross timber 14 by means of strap 32, which 15 passes over the bundle 18 and down around the cross timber 14 at each side of the bundle. Straps 34 are then stretched around the bundles 10 and 18, close to timber 14, drawn taut and clamped. Similar straps 34 are also clamped around the 20 bundles 10 and 18 adjacent the separators 16 and 22 after which bottom cleats 36 are wedged between the bottom bundle 10 and the car side walls 38 and spiked to the cross timbers 6 to prevent transverse movement of the bottom bundle 10. 25 Cleats 40, which are in the form of a parallelogram, are wedged between the bundle 18 and side walls 38 and spiked solidly to cross timber 14 to prevent transverse movement of the top bundle 18.

30 While one embodiment of the invention has been shown and described, it will be apparent that other adaptations and modifications may be made without departing from the scope of the following claims.

35 I claim:

1. The method of preparing a transportation load of heavy metallic strips or the like which are shorter than the car and other heavy metallic strips or the like which are longer than the car 40 for transit in a railway gondola car which method comprises fastening spaced apart cross timbers to the floor of the car, fastening the short strips together to form a bundle, laying the bundle longitudinally of the car on the cross timbers, positioning a long cross timber across the walls of the car at one end, placing a separator on top of the short bundle at the other end of the car, fastening the long strips together to form a bundle, 45 laying the long bundle longitudinally on top of the long cross timber and separator with its end extending from the car at the end having the long cross timber, placing a separator between the bundles at the center of the car, and 50 fastening the long bundle to the short bundle at 55

the cross timbers by means of straps around the bundles.

2. The method of preparing a transportation load of heavy metallic strips or the like which are shorter than the car and other heavy metallic strips or the like which are longer than the car for transit in a railway gondola car which method comprises fastening spaced apart cross timbers to the floor of the car, fastening the short strips together to form a bundle, laying the bundle longitudinally of the car on the cross timbers, positioning a long cross timber across the walls of the car at one end, placing a separator on top of the short bundle at the other end of the car, fastening the long strips together to form a bundle, laying the long bundle longitudinally on top of the long cross timber and separator with its end extending from the car at the end having the long cross timber, placing a separator between the bundles at the center of the car, fastening the long bundle to the short bundle at the cross timbers by means of straps around the bundles, and wedging cleats between the sides of the car and the bundles.

3. The method of preparing a transportation load of heavy metallic strips or the like which are shorter than the car and other heavy metallic strips or the like which are longer than the car for transit in a railway gondola car which method comprises fastening spaced apart cross timbers to the floor of the car, fastening the short strips together to form a bundle, laying the bundle longitudinally of the car on the cross timbers, positioning a long cross timber across the walls of the car at one end, placing a separator on top of the short bundle at the other end of the car, fastening the long strips together to form a bundle, laying the long bundle longitudinally on top of the long cross timber and separator with its end extending from the car at the end having the long cross timber, placing a separator between the bundles at the center of the car, fastening the long bundle to the long cross timber, fastening the long bundle to the short bundle at the cross timbers by means of straps around the bundles, and wedging cleats between the sides of the car and each of the bundles at each end of the car.

4. A transportation load of heavy metallic strips or the like which are shorter than a gondola railway car having cross timbers fastened to the floor thereof and other heavy metallic strips or the like which are longer than the car, which load comprises a bundle of the short strips resting on the cross timbers, a long cross timber resting on the sidewalls of the car at one end, a separator on the short bundle at the other end of the car, a separator on the short bundle between the long cross timber and first named separator, a bundle of the long strips resting on the

long cross timber and separator with its end extending from the car at the end having the long cross timber, and straps around the long and short bundles for fastening them together at the cross timbers.

5. A transportation load of heavy metallic strips or the like which are shorter than a gondola railway car having cross timbers fastened to the floor thereof and other heavy metallic strips or the like which are longer than the car, which load comprises a bundle of the short strips resting on the cross timbers, a long cross timber resting on the sidewalls of the car at one end, a separator on the short bundle at the other end of the car, a separator on the short bundle between the long cross timber and first named separator, a bundle of the long strips resting on the long cross timber and separator with its end extending from the car at the end having the long cross timber, means for fastening the long bundle to the long cross timber, and straps around the long and short bundles for fastening them together at the cross timbers.

6. A transportation load of heavy metallic strips or the like which are shorter than a gondola railway car having cross timbers fastened to the floor thereof and other heavy metallic strips or the like which are longer than the car, which load comprises a bundle of the short strips resting on the cross timbers, a long cross timber resting on the sidewalls of the car at one end, a separator on the short bundle at the other end of the car, a separator on the short bundle between the long cross timber and first named separator, a bundle of the long strips resting on the long cross timber and separator with its end extending from the car at the end having the long cross timber, means for fastening the long bundle to the long cross timber, straps around the long and short bundles for fastening them together at the cross timbers and cleats between the sides of the car and each of the bundles at each end of the car for preventing transverse movement of the load in the car.
